UNITED STATES PATENT OFFICE.

ARTHUR J. BASTIAN, OF EDGEWOOD PARK, PENNSYLVANIA, ASSIGNOR TO WESTINGHOUSE ELECTRIC & MANUFACTURING COMPANY, A CORPORATION OF PENNSYLVANIA.

PROCESS OF AND APPARATUS FOR MOLDING.

Application filed June 9, 1919. Serial No. 302,637.

To all whom it may concern:

Be it known that I, ARTHUR J. BASTIAN, a citizen of the United States, and a resident of Edgewood Park, in the county of 5 Allegheny and State of Pennsylvania, have invented a new and useful Improvement in Processes of and Apparatus for Molding, of which the following is a specification.

My invention relates to molds and it has, 10 for its primary object, the provision of a mold which shall be particularly adapted for utilization in the construction of fairlead bushings, such as are employed in the wireless equipment of aircraft. 15 On account of the unusual construction of fairleads great difficulty has been experienced, heretofore, in properly forming them to obtain sufficient mechanical strength in the resulting article. The fairlead comprises a tubular element which is employed 20 to trail an antenna wire below a plane and this tubular element must be securely mounted upon the fuselage and it must also be insulated therefrom.

25 In order to obtain the desired mechanical strength in the tubular element, which is subjected to relatively great strains by the trailing antenna wire, a metallic tube is employed and this tube is insulated, by superimposing about it layers of fibrous sheet material impregnated with a suitable binder which is adapted to harden under the application of heat and pressure. The metallic tubular element serves as an electrical contact and is secured to the fuselage by means 30 of a suitable insulating receptacle fastened to the tube and adapted to be bolted to the fuselage of the plane.

35 The object of my invention resides, therefore, in providing a mold which may be employed in compacting the material surrounding the metallic tube and to which heat may be applied to cure or harden the binder utilized with the insulating material.

40 A still further object of my invention is to provide a mold in which a fairlead bushing may be molded in substantially one operation, thus promoting rapid production of such articles.

45 With these and other objects in view my invention will be more fully described, illustrated in the drawings, in the several views

of which like numerals indicate corresponding parts, and then particularly pointed out in the claims.

55 In the drawings Figure 1 is a side view, partly in section and partly in elevation, of an inner mold embodying my invention; Fig. 2 is an end view of the inner mold shown in Fig. 1; Fig. 3 is a plan view of a 60 bar employed in closing one end of the mold embodying my invention; Fig. 4 is an end view of the bar shown in Fig. 3; Fig. 5 is a side view of a centering pin employed in my mold; Fig. 6 is an end view of a forming 65 and pressure member employed in my mold; Fig. 7 is a sectional view taken substantially along the line VII—VII of Fig. 6; Fig. 8 is a plan view of a closing member employed 70 with the inner mold shown in Fig. 1; Fig. 9 is a side view of the member shown in Fig. 8; Fig. 10 is a transverse, sectional view of a member adapted to be employed with the 75 pressure member shown in Fig. 6; Fig. 11 is an end view of the member shown in Fig. 10; Fig. 12 is a side view, partially in section and partially in elevation, of an assembled mold embodying my invention, illustrating the disposition of the fairlead which may be molded therein and also the 80 manner of securing the body of the mold to a press platen and Fig. 13 is an end view 85 of the body of the mold shown in Fig. 12.

90 As shown in Figs. 1 and 2, I may employ an inner mold 1 which comprises a plurality of splits 2 having radial faces 3, the splits being so formed that, when placed with the radial faces 3 in engagement, a frusto-conical body is provided. The inner faces of the splits are so grooved as to provide a longitudinal opening 4 communicating with a larger cylindrical opening 5 at one end and with a restricted opening 6 which, in turn, communicates with a relatively large opening 7 at the other end of the assembled inner mold. The radial faces of the splits 2 are, preferably, provided with grooved portions 8 which form over-flow chambers when the inner mold is assembled. The radial faces are also drilled to provide openings 9 to receive dowel pins 10 which are employed to insure simultaneous movement of the splits forming the inner mold when it is disposed in the mold body.

A pressure member 11, which is constructed of suitable dimensions to permit of disposing it in the opening 5 in the inner mold 1, is formed with a central opening 12 and 5 a plurality of smaller openings 13, adjacent its periphery, which are adapted to receive members 14 which carry marking pins 15. As shown in the drawings, the member 11 is formed, at one end, with shoulders 16 for 10 reasons which will be apparent from the description, hereinafter set forth, of the molding operation of the fairlead bushing. In Figs. 10 and 11 is shown a member 17 so formed as to fit within the opening 12 of the 15 pressure member 11. The member 17 is also formed with an opening 18 communicating with a restricted opening 19, the openings 18 and 19 providing a passage through the member 17. The member 17 is also provided with a recess 20.

Referring to Figs 12 and 13, the mold-body 21 comprises a rectangular body provided with a tapered bore 22 extending through the body and adapted to receive the 25 frusto-conical inner mold 1. The walls of the mold body 21 are provided with passages 23, providing means for circulating a heating fluid to heat the mold. A plurality of ears 24 are secured to one end face of the 30 mold body 21 to provide means for securing the mold to a press platen 25. The end of the mold body 21, which carries the ears 24, is provided with a channel 26 adapted to receive a bar 27 and the channel is preferably of greater depth than the thickness of the bar. 35

In employing the mold above set forth, a fairlead bushing is partially preformed by employing a metallic tube 28 about which 40 is superimposed layers of fibrous material 29. The fibrous material is preferably impregnated with a suitable binder, such as phenolic condensation product. The metallic tube 28, and the surrounding fibrous 45 material 29, may be disposed in the opening 4 provided in the assembled splits 2 and a centering pin 30 may be so extended through the metallic tube that its head 31 seats in the opening 6 of the inner mold. 50 A member 32, shown in Figs. 8 and 9, may then be disposed in the opening 7 and secured therein by any suitable means, such as by means of a screw 33. The metallic tube 28 is thus held securely in place in 55 the assembled inner mold and, while thus held in place, a suitable molding composition 36 may be disposed about the end of the tube which extends into the opening 5 of the inner mold 1. The molding composition 36 may comprise wood flour mixed with a phenolic condensation product. 60

The member 17 may be disposed in the opening 12 of the pressure or forming member 11 and a contact member 34 may be disposed upon the end of the member 17 with 65

its threaded projection 35 seated in the recess 20. The member 11 may then be disposed in the opening 5 and, when thus disposed, the centering pin 30 and the metallic tube 28 fit into the openings 18 and 19 of the member 17.

The mold core 1 is now in readiness to be disposed within the body 21 which is preferably secured to the press platen 25 with the bar 27 disposed in place to close the opening at the end of the mold body. The inner mold is forced into the tapered bore of the mold 21 by pressure transmitted by the press platen 25 against a plate (not shown) which is held stationary against the opposite end of the extending inner mold. As the inner mold 1 is forced into the mold body 21, the splits are forced into engagement with the material disposed about the metallic tube contained therein and exert a compacting pressure thereon. The member 11 is also forced into the openings against the molding composition disposed therein and compacts it to form the walls of a receptacle upon the end of the fairlead bushing. Heat is applied together with the pressure to first soften the phenolic condensation product and to then harden it to a substantially insoluble and infusible state. The pins 15 make center marks in the end walls of the recesses, provided in the molding composition, by the members 14. The marks thus made may be utilized as guides when the molded body is drilled to provide openings to receive clamping bolts or screws. 95

A fairlead bushing may thus be molded in substantially one operation although the operation does, strictly speaking, comprise two steps; first, the pressure of the fibrous material surrounding the metallic tube 28 and second the additional pressure utilized in compacting the molding composition employed to form the receptacle at the end of the tube. The channel 26 provided in the mold body 21 is preferably of greater depth than the thickness of the closing bar 27, so that slight play of the latter is allowed and, when the inner mold 1 has been fully advanced into the mold body 21 and the bushing contained therein has been pressed and cured, the inner mold may be easily removed by applying pressure to the bar 27 by means of any suitable implement to start the inner mold 1 out of the mold body 21. 110

Although I have specifically described a mold embodying my invention and pointed out a particular application therefor it is obvious that minor changes may be made in the construction of the mold and various applications may be found therefor and I desire that no limitations shall be imposed except such as are indicated in the appended claims. 115 120 125 130 135 140 145 150 155 160 165 170 175 180

I claim as my invention:—

1. A mold comprising a frusto-conical inner mold including a plurality of splits having radial engaging faces and provided 5 with recesses at each end connected by a central opening, a member adapted to seat in one of said recesses to close one end of the inner mold, a member provided with an opening adjacent its center and a plurality 10 of openings adjacent its periphery adapted to fit within the other recess, a plurality of pins adapted to be disposed within the openings adjacent the periphery of the end member and a body provided 15 with a tapered bore adapted to receive the inner mold.
2. The method of molding articles which comprises providing a mold having a central opening to receive a plunger having an 20 opening that constitutes the matrix of the article to be formed, inserting a preformed body to be molded in a constricted portion of the opening in said plunger, charging the remaining portion of said matrix with a molding composition, inserting a pressure 25 block in one end of said matrix, and applying heat to said mold and pressure to said block and plunger independently to simultaneously compact and consolidate the preformed body and composition. 30
3. The method of molding articles which comprises providing a mold having a central opening adapted to receive a plunger that constitutes the matrix of the article to be formed, charging said matrix with a 35 molding composition, inserting a pressure block in one end thereof and applying heat to said mold and pressure to said block and plunger independently to simultaneously compact and consolidate the composition. 40

In testimony whereof, I have hereunto subscribed my name this 26th day of May 1919.

ARTHUR J. BASTIAN.
